KNOCKDOWN POST CONSTRUCTION

Fred S. Beach and Fitch H. Beach, Charlotte,
Mich.

Application February 3, 1939, Serial No. 254,511

5 Claims. (Cl. 189—28)

This invention relates to that classification of structures comprehending various styles and forms of posts and, as the title implies, we have evolved and produced a sectional or composite construction of the so-called knockdown variety, that is, one in which the post proper can be temporarily disconnected from its supporting base.

Although the improved post construction may be utilized for supporting fence wires and the like, it was primarily adopted for use as a so-called sign post and the outstanding object has been to provide an improved construction characterized by a sheath or socket to be embedded in the ground, the upper end of the socket being substantially level with the ground so that when the post is detached therefrom a grass mowing machine may be driven across it without injury to the cutting blade.

Under present day provisions and adaptations, a sign post supported within the limits of a plot of grass becomes an obstruction adding to the difficulty of cutting the grass within the vicinity of the post. Under our arrangement, by lifting the post out from its supporting socket, the obstruction is temporarily removed, after which the post can be properly replaced to perform its appointed supporting function.

Although the invention as disclosed in the drawing is being constructed of sheet metal it is obvious that the principle applies to concrete constructions, wood constructions and equivalent arrangements.

Other features and advantages will become more readily apparent from the following description and the accompanying illustrative drawing.

In the drawing:

Figure 1 is a perspective view of the sectional post as constructed in accordance with the principles of the present improved invention.

Figure 2 is a view in vertical section with parts in elevation, the post being broken off and there being shown a trip tool or implement inserted for the purpose of releasing the latch.

Figure 3 is a fragmentary perspective view of the lower end of the post, that is, the portion having an aperture forming a keeper for the spring latch or retaining finger.

Figures 4 and 5 are horizontal sections on the lines 4—4 and 5—5 respectively of Figure 1.

Referring now to the drawing by distinguishing reference numerals, the foundation or base unit is denoted by the numeral 6. Broadly, this is in the form of a sheath or socket embedded so

that the upper end is substantially flush with the ground line A. In the arrangement shown, the sheet metal socket comprises a V-shaped channel member 7 having inturned flanges 8 holding in place a cover or closure plate 9. The lower end of the post is suitably pointed as at 10 to facilitate penetrating the ground. The upper open end of the socket or sheath is provided with an inturned lip 11, this being bent from the plate 9 and serving as a triangular closure to guard 10 against earth and extraneous matter finding its way down into the socket. Incidentally the numeral 12 designates wings fastened to the upper end portions of the post, these being suitably shaped to facilitate embedding and to maintain the sheath securely anchored in the ground. Then too, as shown in Figure 2, on the interior of the intermediate portion carried by the plate 9 is a spring pressed finger or latch 13. The free end of this is releasably engageable with an aperture or keeper hole 14 in the lower end portion of the post 15. The post is a sturdy angle iron and this adequately fits tightly in the substantially triangular sheath. Ordinarily, as before stated, the post is utilized to support a vehicle 25 direction sign, signal or the like, 16. It is evident however, that the post may serve in divers ways.

We call attention now to the detent or latch releasing implement or tool 17. This is a simple 30 L-shaped member having a finger grip 18 and a depending stem portion 19, which is slipped down into the post as shown in Figure 2. By forcing it downwardly it will pry the latch loose from the keeper hole 14, thus releasing the post 25 15 so that it can be bodily withdrawn from the sheath or socket into which it normally fits telescopically.

The invention is utmost simplicity itself. The method of construction and use would appear to 40 be obvious from the drawing and preceding description. Under the circumstances, a more elaborate description is considered unnecessary.

As before stated, and as evident from the claims, the question of material utilized in construction is immaterial. That is to say, we are concerned primarily with the particular construction and arrangement rather than precise shape, size and material. The claims are to be construed accordingly.

We claim:

1. In a post construction of the class described, a sheath adapted to be embedded in the ground, said sheath being substantially triangular in cross sectional form, the upper end of the sheath 55

being provided with a laterally projecting triangular closure lip, the apex of which is opposed to and spaced from the crotch portion of the sheath to define a substantially V-shaped slot, a spring 5 latch finger confined in said sheath and secured at one end to that wall of the sheath opposed to the V-shaped crotch portion, the free detent forming end of said latch finger being opposed to and in alignment with said crotch, and a post 10 of V-shaped cross sectional form fitted telescopically in said sheath and having its vertex seated in said crotch, said vertex having an aperture therein forming a keeper hole into which the detent end of said latch finger releasably snaps.

2. In a knockdown post construction of the 15 class described, a relatively stationary tubular sheath pointed at its lower end and provided at its upper end with a restricted entrance slot of a predetermined configuration, said sheath being adapted to be embedded in the ground so that its upper end is substantially flush with the 20 ground level, the body portion of the sheath being imperforate, a spring latch fixedly mounted and wholly confined within the limits of said sheath, a detachable post of a cross-sectional shape 25 corresponding to the shape of the aforementioned slot, the lower end of said post being insertible through the slot to telescope into the sheath and being provided with an aperture forming a keeper 30 hole for reception of the free retention end of said latch.

3. In a knockdown highway safety signal post 35 construction of the class described, a relatively fixed vertically elongated tubular base adapted to be embedded in the ground with its upper end substantially flush with the surface of the ground, said upper end portion being substantially imperforate except for a post accommodation slot, the latter being restricted and of a predetermined 40 configuration, a single spring latch wholly confined within the limits of the imperforate body portion of said base at a point below the slot, one end of said latch being fastened to a predetermined wall portion and the other end being 45 free and flexible, said latch being accessible only by way of said slot, and a detachable post slidably keyed in said slot and depending into the base in parallelism with the latch and corresponding in 50 cross sectional shape to said slot, said post having a keeper seat for the free end of the latch, and the alignment of the latch and keeper seat being determined and maintained by the guiding co-action of the slot and companion post.

4. In a knockdown highway safety signal post 55 construction of the class described, in combination, a sheath adapted to be embedded in the ground, said sheath being triangular in cross-sectional form, the upper end of the sheath being formed with a substantially V-shaped slot the 60 vertex of which is in matched alignment with the crotch of the V-shaped portion of said sheath,

the body portion of the sheath being imperforate, a spring latch-finger secured at one end to the interior wall of the sheath opposed to said crotch and the free end of said latch-finger registering with the crotch, the entire latch-finger being confined wholly in the imperforate body portion of the sheath, a detachable sign-carrying post passing through said slot and depending into the sheath, said post being V-shaped in cross-sectional form, the vertex thereof being aligned with 10 and resting in said crotch and provided at a predetermined point with a keeper hole for releasable reception of the free end of said latch-finger, and a component longitudinally elongated latch releasing and holding member including a 15 V-shaped body portion extending down through the slot with its vertex portion seated in the crotch portion of the post, said member being slidable in relation to the post and slidable in conjunction with the post, the body portion being 20 imperforate, whereby to permit it to be slid between the latch-finger and post to dislodge the latch-finger from the keeper hole and to thereafter cover said keeper hole to permit unobstructed withdrawal of the post and said member unitarily while retaining the latch-finger in its released position.

5. A knockdown post construction of the class 25 described comprising a sheath V-shaped in cross-section adapted to be embedded in the ground, the upper end of the sheath being provided with a laterally projecting triangular closure lip, the apex of which is opposed to and spaced from the crotch portion of the sheath to define a substantially 30 V-shaped slot, a spring latch finger confined in said sheath and secured at one end to that wall of the sheath opposed to the V-shaped crotch portion, the free detent forming end of 35 said latch finger being opposed to and in alignment with said crotch, and a post of V-shaped cross sectional form fitted telescopically in said sheath and having its vertex seated in said crotch, said vertex having an aperture therein forming a keeper hole into which the detent end of said 40 latch finger releasably rests, and a latch releasing member, V-shaped in cross-section having a flanged portion at its upper end and being of a length greater than the distance between the closure lip of the sheath and the detent end of 45 the spring latch finger, fitted telescopically with in the V-shaped crotch portion of the post located in the sheath, whereby, upon exerting a downward pressure on the flanged portion of the latch releasing member, the lower end of said member 50 will contact the spring latch finger and force the detent end out from the keeper hole of the post, thus enabling the post to be readily withdrawn from the sheath.
